UNITED STATES PATENT OFFICE.

GEORGE M. R. TWOSE, OF CHICAGO, ILLINOIS.

HAT-HOLDER.

SPECIFICATION forming part of Letters Patent No. 501,972, dated July 25, 1893.

Application filed June 28, 1892. Serial No. 438,317. (No model.)

To all whom it may concern:

Be it known that I, GEORGE M. R. TWOSE, of Chicago, Illinois, have invented a certain new and useful Improvement in Hat and Coat Hooks, of which the following is a specification.

As is well known, with the ordinary hooks in use for holding hats and coats, in hotels, restaurants, private residences, and other places, there is frequently nothing to prevent one so disposed from carrying the hat and coat away accidentally or intentionally, in the owner's absence. Some means is therefore desired for preventing such errors or thefts, which means should be simple, inexpensive and easily operated, and to that end I have devised my improvement, which, speaking generally, consists of the application to the hook of a locking device, hereinafter more particularly described; and my invention more especially consists in the features, details of construction and combinations hereinafter described and claimed.

In the drawings, Figure 1 is a side elevation of one form of my improvement; and Fig. 2 is a detail of a part thereof.

The hook A may be made in any desired style, either in the ordinary form, as shown in the drawings, or in any special form desired, and is secured to the wall or other support A' by screws or other suitable means. At a point adjacent to and preferably above this hook, I secure an arm B, of any suitable dimensions, which carries a case B', through which passes a slot b, as shown more particularly in Fig. 2.

In the drawings, I have shown a block C as interposed between the arm and the wall or support A', intended to bring the operative parts of the mechanism into proper position relative to the hook A. The device will be preferably used in this form when applied to hooks already in use, the block affording a ready and efficient means for bringing the parts into the proper relative position, without incurring any expense incident to making the arms B of different lengths, and enabling the locking mechanism to be applied to hooks of any sort. If desired, however, special hooks

may be made of the proper length to act with 50 the arms B, without the use of spacing blocks, the arm in between being attached directly to the wall, the only difference from such construction and that shown in Fig. 1 being that the hook A would be shorter, or the arm B 55 lower, the construction and operation of the parts being in either case the same.

Through the slot b passes a rod or bar D, of any desired dimensions, and preferably, though not necessarily, provided with corrugations or notches d on one side. This bar is capable of being slid up and down in the slot, the notches engaging with a spring catch E, shown in Fig. 2, whereby the bar is held at any desired height. The catch E is normally 65 forced out by means of any suitable spring, (not shown) and unless locked, the bar can be slid up and down past the catch with ease. To secure this catch a suitable lock is provided of any desired form capable of being 70 operated by means of a key F. The construction of the lock being such that when the key is inserted, the catch E will be unlocked, being only operated by its spring, but when the key is withdrawn, a bolt will engage with the 75 catch and prevent it from moving.

The device having been constructed and put together as described, operates in the following manner:—The key being inserted, the bar D is first moved upward to allow the hat and 80 coat to be hung upon the hook, being held by the catch; after this the rod is slid down until it approaches so closely to the hook A as to prevent the withdrawal of either the hat or coat, after which the key is withdrawn, locking the bar. It will then be impossible to remove either the hat or coat, without raising the bar, and as this is locked, it is impossible to raise it, without breaking some part of the device. When it is desired to remove the hat 90 and coat, the key is inserted, releasing the bar, which is then raised, allowing the coat to be removed. By this means I provide a simple and efficient device for preventing stealing or accidental carrying away of hats or 95 coats, and the key being numbered may serve as a check, and while I have described more or less precise forms, I contemplate all proper

changes in form, proportions and the substitution of equivalent members.

I claim—

A device of the class described, comprises
5 a horizontal slotted arm attached to a support
above and in line with a garment supporting
hook, a notched bar passing through such slot
and sliding vertically toward and from the

hook to secure and release the garment, and a
means for engaging with the notches in the 10
bar for fastening the same in any desired po-
sition, substantially as described.

GEORGE M. R. TWOSE.
